UNITED STATES PATENT OFFICE.

LAWRENCE O. ROOT, OF EAST MINNEAPOLIS, MINNESOTA.

CLOTHES-RACK.

SPECIFICATION forming part of Letters Patent No. 247,692, dated September 27, 1881.

Application filed December 4, 1880. (Model.)

To all whom it may concern:

Be it known that I, LAWRENCE O. ROOT, of East Minneapolis, in the county of Hennepin and State of Minnesota, have invented a new and valuable Improvement in Clothes-Racks; and I do hereby declare that the following is a full, clear, and exact description of the construction and operation of the same, reference being had to the annexed drawings, making a part of this specification, and to the letters and figures of reference marked thereon.

Figure 1 of the drawings is a top view. Fig. 2 is a front view. Fig. 3 is a vertical central section. Fig. 4 is a detail sectional view.

This invention relates to that class of clothes-driers or clothes-racks in which a bracket secured to the wall, a fence, or other suitable partition is provided with radial arms for supporting the articles to be dried or suspended; and it consists in the improved features of construction and combination, hereinafter fully described, and particularly pointed out in the claim.

In the drawings hereto annexed, A represents a bracket. B is the back-rim, having perforations *a* for bolts for attaching the bracket at any desired place. This rim is to be made in any suitable shape. From arms *b b* there extends a rigid curved support, C, and from the upper ends, *c c*, of arms *b b* there extends a fastening-bar, D, downward from which project pins E. This bar is shorter than the support, and is therefore back of the latter. The support C, as stated, is curved, whereas the bar D is composed of two straight arms, *d d*, forming an angle, *d'*, the relation of the two being that of chords to their arcs. By this construction a greater distance intervenes between the straight arms *d d* and the curved support C than if both the bar and support were straight or curved, which gives a longer bearing.

Support C and bar D are braced by a brace, F, which extends from top to bottom of back-rim B and attached to the middle of said bar

and support. This construction forms a skeleton-frame light, neat, and tasty.

As shown, bar D is not only behind but also above the plane of support C. On each side of brace F there extends downward from bar D pins E, there being usually the same number on each side. This bracket, composed as described, is preferably to be cast in one piece.

H are the rods, which are made with the butts *h*, having a hole, *e*, therethrough, said rods being flat or thicker through one way than the other, and the holes running with the thicker direction. These rods are to be placed with their butt-ends resting on support C, pins E passing into holes *e* the length of said pins, and the depth of said rods being such as to readily allow the rods to be inserted in place and be held firmly there by the pins. To this end the depth of the rods should be the same as the perpendicular distance between the planes of the top of support C and the bottom of bar D, and the pins E should have a length about half this distance, though it is only necessary that said pins should be short enough for the rods to be slipped in place. By this construction the rack can readily be taken apart for packing, and rods not in use can be shoved aside or taken down.

What I claim is—

In a clothes-drier, the bracket A, having rim B, perforated at *aa*, and having the curved support C, fastening-bar D, composed of straight arms *d d*, having downwardly-projecting pins E, and the vertical curved brace F, connecting the rim B, curved support C, and fastening-bar D, in combination with the rods H, having their butts *h* perforated at *e*, substantially as and for the purposes set forth.

In testimony that I claim the above I have hereunto subscribed my name in the presence of two witnesses.

LAWRENCE ODELL ROOT.
